United States Patent

Des. 239,583
Patented Apr. 20, 1976

239,583

CHAIR

Stapleton Long, Morristown, Tenn., assignor to The Berkline Corporation, Morristown, Tenn.

Filed Jan. 2, 1975, Ser. No. 538,174

Term of patent 7 years

Int. Cl. D6—01

U.S. Cl. D6—71

FIG. 1

FIG. 2

FIG. 1 is a front perspective view of a chair showing my new design; and

FIG. 2 is a side perspective view thereof.

The side not shown is a mirror-image of the side shown and the back is plain and conventional.

I claim:

The ornamental design for a chair, as shown and described.
